UNITED STATES PATENT OFFICE.

EUGENE A. BURNS, OF EAST BROOKFIELD, MASSACHUSETTS, ASSIGNOR OF ONE-HALF
TO CLAUDE A. DERR, OF WORCESTER, MASSACHUSETTS.

SHOE-FORM.

1,330,428.

Specification of Letters Patent. Patented Feb. 10, 1920.

Application filed April 9, 1919. Serial No. 288,702.

To all whom it may concern:

Be it known that I, EUGENE A. BURNS, a citizen of the United States, residing at East Brookfield, in the county of Worcester and State of Massachusetts, have invented 5 a new and useful Shoe-Form, of which the following is a specification.

This invention relates to a form for supporting the top of a high shoe in normal 10 position, as for show-window display purposes.

It has been customary to use tissue paper or other similar material for obtaining this result, but this is both laborious and unsatisfactory, as shoes thus prepared promptly lose their desired appearance when handled, as the paper is easily crushed and then requires replacement.

It is the object of my invention to provide 20 a light metal form for this purpose which may be easily and cheaply manufactured, which is neat and effective in use, and which may be readily stored in quantities when not in use.

25 A preferred form of my invention is shown in the drawings, in which—

Figure 1 is a side elevation of my improved form, disposed in a shoe indicated in dotted lines;

30 Fig. 2 is a plan view of the form, and Fig. 3 is a perspective view thereof.

Referring to the drawings, it will be seen 35 that the shoe form in its preferred construction comprises a single piece of wire bent to form an upper loop 10, a lower loop 11 and front portions 12 and 13. The loops 10 and 11 are held in proper spaced relation by side spacing strips 15 and 16, and a back spacing strip 17. These strips are preferably 40 formed of flat metal stock of substantial thickness and have their ends secured to the upper and lower loops in any convenient manner, as by bending the ends closely around the wire loops. The strips may be 45 secured from displacement along the wires by soldering or brazing if desired, and the two ends of the wire may be secured within an end portion of one of the strips, as indicated at 18 (Fig. 1) or may be connected in 50 any other convenient manner.

The front portions 12 and 13, the side strips 15 and 16, and the back strip 17 are

all shaped to conform closely to the outline of the shoe top when the latter is in normal position, and the parts are of sufficient 55 strength and stiffness to maintain their position and hold the shoe top in the desired condition. The wire framework gives a certain amount of resilience to the form, thus permitting it to be easily placed within the 60 shoe. The absence of cross connections between the front portions 12 and 13 permits the forms to be slipped within each other for storage.

Having thus described my invention, it 65 will be seen that I have provided an extremely simple, durable and efficient form for supporting the top of a high shoe in normal position, and that the device possesses many advantages over the devices previously used.

It will be evident that changes and modifications can be made in my invention by those skilled in the art without departing from the spirit and scope thereof as set 75 forth in the claims, and I do not wish to be otherwise limited to the details herein disclosed, but what I claim is:—

1. A shoe form comprising a light wire frame having substantially vertical upper 80 and lower shoe-engaging loops, and substantially vertical members connecting said loops at a plurality of points and each adapted to position the top of a shoe by engagement therewith.

2. A shoe form comprising a light wire frame having the general shape of the inside of a shoe in both horizontal and vertical section, and having side and rear upright members secured at the upper and 90 lower ends to said frame and also adapted to engage and support the top of a shoe within which the form is placed.

3. A shoe form comprising a frame formed from a single piece of wire and having upper and lower loops, and relatively stiff metal spacing strips secured between said loops at the back and sides of said frame and adapted to support a shoe top in 95 normal position.

In testimony whereof I have hereunto affixed my signature.

EUGENE A. BURNS.

It is hereby certified that in Letters Patent No. 1,330,428, granted February 10, 1920, upon the application of Eugene A. Burns, of East Brookfield, Massachusetts, for an improvement in "Shoe-Forms," an error appears in the printed specification requiring correction as follows: Line 80, claim 1, for the word "vertical" read *horizontal*; and that the said Letters Patent should be read with this correction therein that the same may conform to the record of the case in the Patent Office.

Signed and sealed this 9th day of March, A. D., 1920.

[SEAL.]

M. H. COULSTON,

Acting Commissioner of Patents.

Cl. 12—128.
